INVENTOR
Reuben B. Benjamin
By Jones, Addington, Ames, Seibold Attest.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PANEL BOARD.

Application filed June 14, 1920. Serial No. 388,827.

To all whom it may concern:

Be it known that I, REUBEN B. BENJAMIN, a citizen of the United States, residing at Chicago, in the county of Cook and State 5 of Illinois, have invented new and useful Improvements in Panel Boards, of which the following is a full, clear, concise, and exact description, reference being had to the accompanying drawing, forming a part of 10 this specification.

My invention relates to panel boards and it has especial relation to standard and interchangeable units for use in boards of the character designated.

15 One object of my invention is to so form a panel board unit that branch circuits may be derived therefrom from either a two-wire or a three-wire circuit without involving a great deal of re-organization. In this 20 connection it is desirable that fuse receptacles are provided whereby both sides of the branch lines which are connected to the board unit may have a fuse inserted therein. By constructing a panel board unit in 25 accordance with my invention this protection is provided irrespective of the number of wires in the main circuit.

I attain this object by forming the center contacts of some of the receptacles integrally with the respective bus bars to 30 which they are connected. Again, means are provided whereby a neutral bus-bar may be connected to either set of receptacles.

The panel board unit comprises an insulating base member with which the receptacles and bus-bars are so associated that the neutral bus member may be used or disregarded, as desired. To this end, I provide channels in the insulating base which 35 are so formed that connecting members may be seated therein whereby any desired connections may be obtained.

The bus bars which are positioned on the aforementioned base section are provided at 40 both ends with interfitting slots whereby a number of my base sections may be built together to form a unitary panel board of any desired capacity.

It is another object of my invention to so 45 associate with the aforesaid base section, or any number of them, recessed cap portions which register with the base portions and, by covering all of the line portions of the latter, constitute a dead front panel board.

50 Both of the aforesaid portions, that is the

cap portion and base portion, are provided with securing means whereby the two sections may be firmly held together.

Finally, it is an object of my invention to provide a casing for the built-up panel 60 board, comprising base and cap portions as above described, whereby it is effectively enclosed. At the same time, I so arrange the casing with respect to the panel board 65 itself that a commodious space is provided for the disposition of wiring leads.

For a better understanding of my invention reference may be had to the accompanying drawings, in which:

Fig. 1 is a plan view of a panel board constructed in accordance with my invention, and a containing casing therefor, a hinged cover for said casing being opened; 70

Figs. 2 and 3 are elevational sectional views taken on the line 2—2 of Fig. 1 and 75 line 3—3 of Fig. 2, respectively;

Fig. 4 is a plan view of a base section embodying my invention, the neutral or central bus-bar being shown as connected to the branch circuits; 80

Fig. 5 is a fragmentary sectional view taken on the line 5—5 of Fig. 4, showing the method by which the branch wiring leads are connected to the shell contacts of the base-section receptacles; 85

Fig. 6 is a plan view of a base section embodying my invention, the neutral or central bus-bar not being connected to the branch line system; 90

Fig. 7 is an elevational view taken on the line 7—7 of Fig. 6;

Fig. 8 is an elevational sectional view taken on the line 8—8 of Fig. 6;

Figs. 9 and 10 are fragmentary, elevational, sectional views of a portion of the 95 casing and a portion of a cap member, illustrating two methods of constructing the casing to co-act with the cap portions to form a wiring gutter; and

Figs. 11 and 12 are fragmentary views 100 illustrating the manner in which portions of the cap are provided with knock-outs.

A casing comprises a main, dished body portion 20 and a cover 21 associated therewith. The latter is formed with an opening 105 which may be closed by a hinged lid 22. Beneath the lid 22 is positioned a panel board which is substantially commensurate with the opening in the cover 21.

The panel board comprises a base section 110

23 and a cap section 24, the latter being formed with up-standing portions 25—25 constituting barriers whereby the sides of the dished portion 20 of the casing and said 5 barriers form wiring gutters as shown at the right of Fig. 2.

Referring now to Figs. 3, 4, 5, 6, 7 and 8, the base section 23 has bus-bars 26, 27 and 28 mounted thereupon. The base section 23 10 is so molded that the buses 26 and 28 may alternately over- and under-lie the same. As shown most clearly in Fig. 7, a portion 29 of the bus 26 is so formed on an overlying portion thereof that it constitutes a center 15 contact for a receptacle 30, said receptacle being also provided with a shell contact 31. By reference to Fig. 7 it will moreover be observed that the underlying portion of the bus 26 is completely insulated from a receptacle 20 tackle 32 lying in the same vertical plane as said bus 26. The ends of the buses are all provided with slots and threaded securing means whereby any number of sections such as 23 may be secured together, and the bus-bars 25 thereupon form continuous conducting members.

The bus-bar 28 is also provided with over- and under-lying portions, a center contact 33 for a receptacle 34 being formed integrally with the overlying portion thereof. It will be observed, however, that the position of the under- and over-lying portions of the two bus-bars above referred to are so reversed that the receptacles embodying 35 center contacts formed integrally with the buses are positioned at diagonally opposite corners on the base 23. A receptacle 35 is positioned in the plane of the bus 28 and, it will be observed, is diagonally opposite the receptacle 32.

Transverse channels 36 and 37, and a diagonal channel 38, are formed in the base 23. An integral member 39 which is adapted to be seated in the channel 38, extends into and forms center contacts 40 and 41 for the receptacles 32 and 35, respectively.

By reference to Fig. 3 it will be observed that the bus-bar 27 may be electrically connected to the diagonally-extending connector 39 by a screw 42. A connector 43 is seated in the channel 36 and serves to connect the overlying portion of the bus 26 to the center contact 41, the latter being 55 formed integral with said connector. In an analogous manner in Fig. 6 a connector 44 is seated in the channel 37 and serves to connect the overlying portion of the bus 28 to the center contact 40, the latter likewise being formed integrally with the connector 44.

Each of the receptacles, above described, comprises a comparatively short shell contact 31 or 45 and flange portions 46 and 47 60 formed integrally therewith: Passing

through the portion 46 are two screws 47 which serve to draw a plate 48 toward the flange portion thereby firmly securing a lead 49 in electrical contact with the shell portion of the receptacles. This particular construction of shell contact is quite advantageous for the reason just described as well as because of the facility with which the outwardly extending flange member is screwed to the base section. 75

Moreover, a receptacle of this character differs in a large degree from those of the prior art in that the fuse plug passes completely through the shell portion 45 and down onto the center contact, the latter being at a lower level than the bottom of the threaded portion. There is, therefore, a considerable air space between the shell and center contacts of receptacles made in this manner. Again, as illustrated at 80 the right of Fig. 7, the bus bar of different potential passes under the receptacles at still another level whereby what may be termed a "through-level" base is formed. This separation of portions of different potential on different levels is extremely 85 advantageous, especially in a panel board because of the protection thereby afforded against short circuits when a fuse blows out, as well as insuring better insulation 90 in the panel board as a whole, with a minimum space consumption. 95

The cap portion 24 is adapted to register with the base section and its associated equipment and is, therefore, apertured at 50—50 to receive the shell contacts heretofore described. In this manner, a dead front panel-board is formed and, at the same time, as heretofore pointed out, the barriers which are formed integrally with the cap portion assist in establishing commodious wiring gutters in the casing which surrounds the panel sections. These cap portions may be made in any desired size, that is, there may be a cap portion for each 100 individual base section or, as shown in Fig. 2, a cap portion may extend over two base sections. In Fig. 1, I have shown one set of apertures on the cap portion as provided with knock-outs 51, which may be removed 105 when a base section is positioned beneath that portion of the cap. Two varieties of these knock-outs are illustrated in Figs. 11 and 12.

While the provision of barriers 25 results in an extremely simple structure, it may be desirable, in some cases, to form a wiring gutter by bending a portion 52 of the cover 21 downwardly as shown in Figs. 9 and 10, and so molding the cap piece 24 that the 110 bent portion 52 fits snugly therewith. 120

From a consideration of Figs. 4 and 6 it will be seen that, by forming a base section, as shown, and by associating therewith a plurality of receptacles and buses as here- 130

tofore pointed out, a base section, admitting of the connection of branch circuits to either a three-wire or a two-wire system, is formed. The change from one system to another 5 is simply effected by changing the connectors and, inasmuch as the center of the receptacles are all formed integrally with portions of the bus-bars or connectors, a minimum number of parts are employed.

10 Assuming that it is desired to derive branch circuits from a three wire system it will be observed that a fuse receptacle is positioned in the outgoing circuit and in the return circuit. By simply changing the 15 connectors as shown in Fig. 6, two branch circuits may be derived from a two-wire system, the same base section being used and fuse receptacles will be positioned in each of the outgoing and each of the in- 20 coming branch lines.

Tracing connections, for instance, from a three-wire system, as shown in Fig. 4, the current will flow from bus 26 through center contact 29, through the fuse connected thereto, the shell contact 31, the outgoing line of the branch circuit positioned at the left of the base 23 back to the shell contact 45 of the receptacle 32, through the fuse screwed therein into the center contact 40, 25 through the connector 39, down the screw 42, and into the neutral bus 27. A circuit from the bus 28 and the center contact 33 formed integrally therewith, may be traced in an analogous manner through a branch 30 circuit positioned at the right of the base 23.

It will be observed, as above pointed out, that two fuses are positioned in each branch circuit, one in the outgoing line and one in 40 the returning.

When it is desired to derive branch circuits from a two wire system the connecting members 43 and 44 are positioned as shown in Fig. 6, the diagonal connector 39 45 being removed from its channel. A branch circuit to the left in this figure may be traced from the bus 26 through a fuse in the receptacle 30, out through a branch circuit and returning therefrom to the shell 50 contact of the receptacle 32, into the center contact 40 through the connector 44, and thence into bus-bar 28. In the branch circuit just traced fuses were inserted therein at the receptacles 30 and 32. Again, tracing from the bus bar 26 a branch circuit may be derived at the right of the base 23 as follows:

From the bus 26 though the connector 43, the center contact 41, the fuse in the receptacle 35, out through a branch circuit and returning therefrom through the shell contact of the receptacle 34, through the fuse positioned in the latter, and into the bus 28 60 through the center contact 33. In the branch circuit last traced it will be observed

that the fuses positioned on the receptacles 34 and 35 are positioned whereby the requirements, heretofore pointed out for circuits of this character, are satisfied.

While I have described but one embodiment of my invention it is apparent that many modifications therein may occur to those skilled in the art and I desire, therefore, that my invention be construed broadly and limited only by the showing of the prior art and by the scope of the appended claims.

Having thus described my invention, what I claim as new and desire to secure by Letters Patent is:

1. In a device of the character described, a base member provided with a plurality of receptacles arranged on both sides of the medial line, buses associated with said base and said receptacles and being provided with means whereby a plurality of said bus members may be connected together to form a sectionalized receptacle board, some of said buses being provided with portions which function as the center contacts of some of said receptacles, and means whereby the other bus may be connected to form center contacts in the remaining receptacles. 85

2. In a device of the character described, a base member provided with a plurality of receptacles arranged on both sides of the medial line, buses associated with said base and said receptacles and being provided with means whereby a plurality of said bus members may be connected together to form a sectionalized receptacle board, some of the said buses associated with said receptacles functioning as the center contacts thereof, and means whereby the other bus may be connected to form center contacts for the remaining receptacles, said means comprising a member which may be connected to the appropriate bus and which has formed integral therewith portions which function as the center contacts of the remaining receptacles. 100

3. In a device of the character described, a base member having a plurality of receptacles comprising shell and center contacts associated therewith, buses mounted on said base, means on said base admitting of the connection of the center contacts of transversely opposite receptacles, and means permitting the connection of the center contacts of receptacles, diagonally situated with respect to each other, to the centrally located bus. 115

4. In a device of the character described, a base member having a plurality of receptacles associated therewith, buses mounted on said base in substantially parallel relation, the outside buses having alternate portions over-lying and under-lying the top and bottom of said base, the over-lying portions being formed integrally with center contacts 125 130

- of some of the receptacles positioned in the same planes.
5. In a device of the character described, a base member having a plurality of receptacles associated therewith, buses mounted on said base in substantially parallel relation, the outside buses having alternate portions overlying and under-lying the top and bottom of said base, respectively, and the central bus being entirely underlying, the overlying portions of said outside buses being formed integrally with the center contacts of some of the receptacles positioned in the same planes.
10. In a device of the character described, a base member having a plurality of receptacles associated therewith, buses comprising portions forming center contacts for some of said receptacles and having portions overlying and under-lying said base, and another bus entirely underlying said base, said base having channels formed therein to receive connecting members to be seated in some of said channels for connecting said outside buses to the center contacts of the other receptacles.
15. 6. In a device of the character described, a base member having a plurality of receptacles associated therewith, buses mounted on said base, in substantially parallel relation, the outside buses having alternate portions overlying and under-lying the top and bottom of said base, respectively, and the central bus being entirely underlying, the overlying portions of said outside buses being formed integrally with center contacts of some of the receptacles positioned in the same planes, and means admitting of the connection of said central underlying bus to the center contacts of the other receptacles in said outside bus planes.
20. 7. In a device of the character described, a base member having a plurality of receptacles associated therewith, buses mounted on said base, in substantially parallel relation, the outside buses having alternate portions overlying and under-lying the top and bottom of said base, respectively, and the central bus being entirely underlying, the overlying portions of said outside buses being formed integrally with center contacts of some of the receptacles positioned in the same planes, and integral connecting members extending into, and forming the center contacts of, the other receptacles in said planes.
25. 8. In a device of the character described, a base member having a plurality of receptacles associated therewith, buses comprising portions forming center contacts for some of said receptacles and having portions overlying and under-lying said base, and another bus entirely underlying said base, said base having channels formed therein in which members connecting the other receptacles to said buses may be positioned.
30. 9. In a device of the character described, a base member having a plurality of receptacles associated therewith, buses comprising portions forming center contacts for some of said receptacles and having portions overlying and under-lying said base, and another bus entirely underlying said base, said base having channels formed therein in which members connecting the other receptacles to said buses may be positioned, and means comprising an integral member seat-
- ed in one of said channels for connecting the underlying bus to the center contacts of the other receptacles.
35. 10. In a device of the character described, a base member having a plurality of receptacles associated therewith, buses comprising portions forming center contacts for some of said receptacles and having portions overlying and under-lying said base, and another bus entirely underlying said base, said base having channels formed therein to receive connecting members to be seated in some of said channels for connecting said outside buses to the center contacts of the other receptacles.
40. 11. In a device of the character described, a base member having a plurality of receptacles associated therewith, buses comprising portions forming center contacts for some of said receptacles and having portions overlying and under-lying said base, and another bus entirely underlying said base, said base having channels formed therein to receive connecting members to be seated in some of said channels for connecting said outside buses to the center contacts of the other receptacles.
45. 12. In a device of the character described, a base having a plurality of buses mounted thereupon, a plurality of fuse receptacles, some of said buses having alternate portions overlying and under-lying said base, the overlying portions forming the center contacts of some of said receptacles, means whereby two branch circuits may be derived from said device in either a three-wire or a two-wire circuit, each branch circuit embodying at least two fuses therein, irrespective of the character of the main circuit.
50. 13. In a device of the character described, a base, three buses and four fuse receptacles mounted thereupon, some of said buses having alternate portions overlying and under-lying said base, the overlying portions forming the center contacts of some of said receptacles, means whereby a branch circuit may be derived from each side of said base in either a three-wire or a two-wire circuit, each branch circuit having a fuse in the outgoing side and a fuse in the return side, irrespective of the character of the main circuit.
55. 14. In a device of the character described, a base member having a plurality of receptacles, and bus bars having portions overlying and under-lying said base associated therewith, the shell contacts of said receptacles, the center contacts of the receptacles, and the underlying portions of the buses being positioned in three distinct levels.
60. 15. In a device of the character described, a base member having a plurality of receptacles and bus bars having portions overlying and under-lying said base associated therewith, the lower edge of said receptacle shell

contacts being positioned somewhat above the center contacts of the same receptacles, and the underlying portions of the buses being below said center contacts.

16. In a device of the character described, a base member, a plurality of bus-bars associated therewith, fuse receptacles adapted for connection with said bars, and means comprising interchangeable elements and adapted for connecting said receptacles to said bus-bars to eventuate either a three-wire or a two-wire system, as desired.

17. In a device of the character described, a base member, a plurality of bus-bars associated therewith, fuse receptacles adapted for connection with said bars some of the receptacles having permanent connection with two of said bars, and means comprising interchangeable connecting elements to permit of either the connection of the remaining receptacles to the opposite one of the two bus-bars to eventuate a two-wire system, or the connection of said remaining receptacles to a bar other than said above mentioned two bars to eventuate a three-wire system.

18. In a device of the character described, a base member, three bus-bars positioned thereupon, receptacles mounted thereon and connected to the outside of said bars, other receptacles mounted thereon and adapted for proper connection with said bars to eventuate either a two or three-wire system, as desired, and means comprising interchangeable members whereby said receptacles may, at will, be connected as stated.

19. In a device of the character described, a base member, three bus-bars positioned thereupon, receptacles mounted thereon and connected to the outside of said bars, other receptacles mounted thereon and adapted for proper connection with said bars to eventuate either a two or three-wire system, as desired, by means comprising interchangeable members whereby said receptacles may, at will, be connected as stated, one of said members adapted to extend from one receptacle to another and be connected to the middle bus-bar whereby a three-wire system may be formed, and the others of said members being adapted to extend from one receptacle to the opposite outside bus-bar for two-wire connection.

20. In a device of the character described, a base member, three bus-bars positioned thereupon, receptacles mounted thereon and connected to the outside of said bars, other receptacles mounted thereon and adapted for proper connection with said bars to eventuate either a two or three-wire system, as desired, by means comprising three interchangeable members whereby said receptacles may, at will, be connected as stated, one of said members adapted to ex-

tend from a receptacle on one side of the middle bus-bar to receptacles on the opposite sides of said bus-bar and be connected to said middle bus-bar to eventuate a three-wire system, and the other two members 70 adapted to extend from bus-bars to receptacles on the opposite sides of the base to eventuate a two-wire element, said members being formed to establish the center contacts of the receptacles with which they 75 are associated.

21. In a device of the character described, a base member, three bus-bars positioned thereupon, receptacles mounted thereon and connected to the outside of said bars, other 80 receptacles mounted thereon and adapted for proper connection with said bars to eventuate either a two or three-wire system, as desired, by means comprising interchangeable members whereby said receptacles may, at will, be connected as stated, one of said members adapted to extend from one receptacle to another and be connected to the middle bus-bar whereby a three-wire system may be formed, and the others of 85 said members being adapted to be connected from one receptacle to the opposite outside bus-bar for two-wire connection, said base being provided with channels or grooves for the reception of any of said 90 members which it is desired to use.

22. In a device of the character described, a base member, three bus-bars positioned thereupon, receptacles mounted thereon and connected to the outside of said bars, other 100 receptacles mounted thereon and adapted for proper connection with said bars to eventuate either a two or three-wire system, as desired, by means comprising interchangeable members whereby said receptacles may, at will, be connected as stated, one of said members adapted to extend from one receptacle to another and be connected to the middle bus-bar whereby a three-wire system may be formed, and the others of 105 said members being adapted to extend from one receptacle to the opposite outside bus-bar for two-wire connection, said base being provided with channels or grooves for the reception of any of said members which it 110 is desired to use, said grooves extending between the receptacles and buses to be connected and being formed of somewhat the same configuration as to receive, for any particular connection, only the correct connecting member therefor.

23. A panel board construction comprising an insulating base, center and shell contacts for fuse receptacles mounted on said base, and a cover for said shell contacts 125 overlying said base, readily removable from said contacts and having openings in which said contacts lie to permit the entrance of the fuse plugs, the plane of the inner edges of said shell contacts lying a substantial dis- 130

- 6
24. A panel board construction comprising an insulating base, center and shell contacts for fuse receptacles mounted on said base, and a cover for said shell contacts overlying said base, readily removable from said contacts and having openings in which said contacts lie to permit the entrance of the fuse plugs, the plane of the inner edges of said shell contacts lying a substantial distance outwardly from the plane of the center contacts, said shell contacts having outwardly extending flanges seated on said base between said base and cover. 15
25. A panel board construction comprising an insulating base, center and shell contacts for fuse receptacles mounted on said base, and a cover for said shell contacts overlying said base, readily removable from said contacts and having openings in which said contacts lie to permit the entrance of the fuse plugs, the plane of the inner edges of said shell contacts lying a substantial distance outwardly from the plane of the center contacts, said shell contacts having outwardly extending flanges seated on said base between said base and cover, said flanges being provided with wiring terminals. 20
26. A panel board construction comprising an insulating base, center and shell contacts for fuse receptacles mounted on said base, and a cover for said shell contacts overlying said base, readily removable from said contacts and having openings in alignment
- with said shell contacts to permit the entrance of the fuse plugs, the plane of the inner edges of said shell contacts lying a substantial distance outwardly from the plane of the center contacts. 40
27. A panel board construction comprising an insulating base having plug receiving recesses therein, and provided with shoulders adjacent said recesses lying in a plane substantially above the bottom of said recesses, a center contact in each recess substantially below the plane of said shoulders, a plurality of threaded shell contacts, one for each recess, each shell contact having an outwardly extending flange extending from its lower edge and resting on one of said shoulders. 45
28. A panel board construction comprising an insulating base having plug receiving recesses therein, each recess being provided with a shoulder intermediate the top and bottom of the recess, a center contact in each recess substantially below said shoulder portion, a plurality of threaded shell contacts, one for each recess, each shell contact having an outwardly extending flange extending from its lower edge and resting on said shoulder, a binding terminal adjacent said flange, said base being provided with passages for the branch wires leading from said binding terminal to the edge of the base. 50

In witness whereof, I have hereunto subscribed my name.

REUBEN B. BENJAMIN.
